GRAINING

Walter G. Bihler and Howard J. Schuld, Detroit,
Mich., assignors to General Motors Corporation,
Detroit, Mich., a corporation of Delaware

Application June 27, 1936, Serial No. 87,691

12 Claims. (Cl. 101—35)

This invention relates to graining. It is now quite common to grain hollow-ware such as containers, boxes and particularly the garnish molding used on automobile windows by means of a machine having upright rolls and a horizontal table. The work is placed over the end of one roll or one set of rolls and rests on the table. If the work is being grained on the inside, it has to be placed over a roller set, to-wit: one transfer impression roll and one engraved roll. If the work is to be grained on the outside, it is placed over the pressure roll. So far as we are aware, operations of this kind have always heretofore been done with plain cylindrical impression rolls. This has made it difficult to get good grain effects on rounded surfaces such as the turned in surfaces of the garnish molding. If the operator presses the rounded surface deeply into the transfer roll, then the graining lines are somewhat distorted.

One way of meeting the difficulty of the rounded edge portions of the garnish molding has been to separately grain each edge as well as the intermediate zone of the molding, this requiring three separate passages of the molding over a transfer roll. Another way has been to grain the center zone by the usual upright rolls and then "smoke" the edges, that is, spray a dark lacquer on the edges to cover the lack of grain effects at the edges.

It is the object of the present method and machine to grain a rounded surface, particularly the rounded surface of the garnish molding which is exposed to view, with a graining effect which is substantially undistorted and which can be performed in the same operation which grains the center zone of the molding. To this end, we use the apparatus and the method hereinafter detailed.

40 In the drawings:

Fig. 1 is a side elevation of the machine, partly in section.

Fig. 2 is a plan view.

Fig. 3 is a diagrammatic view showing how the 45 molding goes through the rolls.

Fig. 4 is a detail vertical section through the rolls.

Fig. 5 is a section on the line 5—5 of Fig. 4.

Fig. 6 is a plan view of the devices shown in 50 Fig. 4.

Fig. 7 is a section on the line 7—7 of Fig. 4.

Referring to Fig. 4, 1 is the etched roll having etched thereon a photogravure-reproduced image, made by photographing stained natural wood, 55 making a positive from the negative, then expos-

ing a carbon tissue coated with gelatine which has been sensitized by bi-chromate of potassium solution to light through a screen, then exposing the tissue to light through the positive. This light renders the portions of the sensitized gelatine which have been exposed to the light insoluble in water. When the carbon tissue has been squeegeed upon the roll to be engraved, the tissue backing may be soaked off with warm water as well as the soluble gelatine. This leaves the insoluble portions that have been exposed to light as an acid resist which can resist the penetration of the etching fluid which is usually ferric chloride, where a copper plate or roll is used. This affords an intaglio image of the article 10 photographed, with a large number of minute pits or pockets to take the ink. This is the well-known photogravure process which has been used for years in printing the illustrated supplements of newspapers and the better pictorial reproductions in magazines. This photogravure process 15 has been employed for quite some time in reproducing graining effects from natural wood. This etched roll is contacted with a soft elastic or gelatine roll 2 which has been common for years in so-called offset printing. The work is shown at W and this is pressed up against the gelatine or impression roll by a pressure roll 3 which is operated by the foot pedal 4 through the inner connecting link and crank members 20 30 that are plainly shown in Fig. 1, described hereinafter. The set-up of etched roll 1, transfer roll 2, and pressure roll 3 is nicely shown in Fig. 3 where it is seen how this group of rolls is related to the work W.

Now so much of the machine is old practice. The improvement here claimed involves the end formation of the transfer roll and the instrumentalities for guiding it into proper relation with the etched roll and bending it over a curved 40 surface. This is nicely shown in Fig. 4 where it will be seen that the elastic transfer roll extends way beyond its core 5 contrary to the usual practice. This unsupported end extension is tapered 45 outwardly. A conical guide roll 6 fits into this tapered end extension and keeps the elastic roll pressed against the engraved roll, and segments 30 keep the end extension from being unduly distorted by stretching. Diagrammatically opposite this guide roll 6 is a special pressure roll 7 50 contoured to press and guide the tapered end extension of the transfer roll over the curved edge of the work as is plainly shown in Fig. 4. This roll is carried on a movable support 8 which is guided up and down in a fixed support 9. This 55

member 8 has a dovetail straddle of the fixed support 9 as shown at 10 in Fig. 6. The walking beam 11 connects this movable support with a reciprocating rod 12 which connects through the 5 bell cranks and leverage plainly shown in Fig. 1 with the pedal 4 so that every time the pressure roll 3 is pressed in engagement with the work simultaneously the pedal operates the levers 13 and 14 respectively which operate the connections to the main pressure roll 4 and the auxiliary contoured pressure roll 7. Hence both rolls go into operation simultaneously, the main pressure roll 3 to press the garnish molding into the transfer roll and the auxiliary contoured pressure roll 7 for turning or folding the extended 10 tapered end of the transfer roll over the curved edge portion of the garnish molding. This results in bringing the grained impression into contact with the contoured surface with not a great amount of distortion and it permits the 15 graining of contoured surfaces with a regularity and a naturalness of the grain that has not heretofore been possible.

When the pedal 4 is depressed, both the pressure roll 3 and auxiliary roll 7 are brought onto the work at one time provided the foot pressure is exercised on the left hand half of the pedal. However, if the foot pressure is exercised on the right portion of the foot pedal 4 as shown in 20 Fig. 1, then only the rod 31 which controls the pressure roll 3 will be operated and the auxiliary roll 7 will be released and allowed to rise. This is desirable where molding is being grained which contains on part of the molding, a panel or apron 25 such as is very often used on the lower sash of a window molding. This restores the roll to its cylindrical form in place of turning out the end of the roll over the curved molding. Hence, the operator when the work comes to the apron portion 30 can simply shift his foot over to the right side of the pedal and this will release the auxiliary roll. It will be noted that the lever 32 has a cam-like portion 33 that engages with the member 34 on the lever 35 which controls the pressure roll 3. This firmly holds the pressure roll 35 in engagement with the work as it constitutes a substantially irreversible operating connection.

What we claim is:

1. The method of printing on contoured surfaces with an elastic roll having the elastic material overhanging at the end of the roll which comprises the forcing of the overhanging end of the elastic material into a contour approximating the contour of the surface to be printed upon 55 and into contact with such surface.

2. The method of printing on contoured surfaces with an elastic roll having the elastic material projecting at the end of the roll which comprises the folding or turning of the projecting 60 elastic material into contact with the contoured surface.

3. The method of printing on contoured surfaces with an elastic roll having the elastic material overhanging at the end of the roll which 65 comprises the folding or turning of the overhanging elastic material into contact with the contoured surface by a pressure roll.

4. The method of printing on contoured surfaces with an impression roll having an end overhanging the core and tapered inwardly from the outside to the end of the core which comprises applying the work to the surface of such elastic impression roll by means of pressure substantially perpendicular to the surface of the work, then 70 simultaneously applying an oblique pressure to

the tapered inside of the overhanging end of the elastic material of the impression roll, thus folding or turning said impression roll at this point down over the contour of the work.

5. An apparatus for graining or printing on 5 contoured work, the combination of an etched roll, an elastic transfer roll in contact with the etched roll and having a recess at the end of the elastic material on the roll to provide a flexible overhanging end portion and means for turning 10 the overhanging elastic portion of the roll outwardly over the contour of the work.

6. An apparatus for graining or printing on 15 contoured work, the combination of an etched roll, an elastic transfer roll in contact with the etched roll and having a recess at the end of the elastic material on the roll to provide a flexible overhanging end portion and means for turning the overhanging elastic portion of the roll outwardly over the contour of the work, said means 20 comprising a contour roll.

7. An apparatus for graining or printing on 25 contoured work, the combination of an etched roll, an elastic transfer roll in contact with the etched roll and having a recess at the end of the elastic material on the roll to provide a flexible overhanging end portion and means for turning the overhanging elastic portion of the roll outwardly over the contour of the work, said means comprising a pressure roll for turning the elastic 30 material over the contour of the work and a guide roll for engaging the overhanging elastic portion and moving the same into contact with the impression roll.

8. An apparatus for graining or printing on 35 contoured work, the combination of an etched roll, an elastic transfer roll in contact with the etched roll and having a recess at the end of the elastic material on the roll to provide a flexible overhanging end portion, means for turning the overhanging elastic portion of the roll outwardly over the contour of the work comprising a contour roll, and means within the control of the operator for applying said last mentioned means 40 to the overhanging elastic portion of the impression roll or withdrawing the same therefrom.

9. An apparatus for graining or printing on 45 contoured work, the combination of an etched roll, an elastic transfer roll in contact with the etched roll and having a recess at the end of the elastic material on the roll to provide a flexible overhanging end portion, means for turning the overhanging elastic portion of the roll outwardly over the contour of the work comprising a contoured roll, means within the control of the operator for applying said contoured roll to the overhanging elastic portion of the impression roll or withdrawing said roll therefrom, and a second means within the control of the operator for applying a direct substantially perpendicular pressure to force the work into engagement with the 55 elastic impression roll.

10. An apparatus for graining or printing on 60 contoured work, the combination of an etched roll, an elastic transfer roll in contact with the etched roll and having a recess at the end of the elastic material on the roll to provide a flexible overhanging end portion, means for turning the overhanging elastic portion of the roll outwardly over the contour of the work, said means comprising a contoured roll, means within the control of the operator for applying said contoured roll to the inside of the overhanging elastic portion of the impression roll or withdrawing said roll therefrom, and a second means within the control of the operator 65 for applying a pressure substantially perpendicular to the surface of the work, then simultaneously applying an oblique pressure to

the operator for applying a direct substantially perpendicular pressure to force the work into engagement with the elastic impression roll, the two said means within the control of the operator 5 operable simultaneously by reason of being connected together.

11. An apparatus for graining or printing on contoured work, the combination of an etched roll, an elastic transfer roll in contact with the 10 etched roll and having a recess at the end of the elastic material on the roll to provide a flexible overhanging end portion, means for turning the overhanging elastic portion of the roll outwardly over the contour of the work, said means comprising a contoured roll, means within the control of the operator for applying said contoured roll to the inside of the overhanging elastic portion of 15 the impression roll or withdrawing said roll therefrom, and a second means within the control of the operator for applying a direct substantially perpendicular pressure to force the work into engagement with the elastic impression roll, and 20 pedal means for operating the two controls simultaneously.

tanecously or optionally operating only the said second means applying the perpendicular pressure.

12. An apparatus for graining or printing on contoured work, the combination of an etched roll, an elastic transfer roll in contact with the etched roll and having a recess at the end of the elastic material on the roll to provide a flexible overhanging end portion and means for turning the overhanging elastic portion of the roll outwardly over the contour of the work, said means comprising a pressure roll for turning the elastic material over the contour of the work and a guide roll for engaging the overhanging elastic portion and moving the same into contact with the impression roll, and means for engaging the inside 10 of the end portion of the elastic material to prevent the distortion of the same between the guide roll and the said pressure roll which turns the elastic material over the contour of the work. 15
